HAIR CLIPPER

Application filed December 28, 1928. Serial No. 329,009.

The present invention relates to hair clippers.

The object of the invention is to provide a novel and improved automatically operated hair clipper which will be more efficient and reliable in operation than clippers of this type previously developed, which will be light and compact in construction so that it may be easily handled by an operator and which will be relatively inexpensive to manufacture.

The invention is intended primarily as an improvement in electrically driven hair clippers of the vibratory type which are designed to run in synchronism with an alternating current and which comprise an electro-magnet and a vibrating armature. Hair clippers of this type are commonly designed to operate with an ordinary 110 volt, 60 cycle alternating current so that the movable cutter blade is driven at a speed of approximately 7,200 vibrations a minute. At this high speed there is a tendency for the clipper to develop excessive vibration with consequent objectionable noise and wear and tear on the parts. Also, on account of the high speed, difficulty is experienced in producing a clipper in which the movable cutting blade will have a uniform and sufficiently wide amplitude of movement during the operation of the clipper.

To remedy these and other defects of prior clippers of the vibratory type, an important feature of the present invention consists in the provision of an armature for actuating the movable blade of the clipper which is pivotally mounted intermediate its ends, and in arranging the poles of the electro-magnet on opposite sides of the armature and at opposite sides of the pivot. A balanced pull on the armature about its pivot is thus secured with an exceptionally compact and efficient arrangement of the parts whereby wear on the armature pivot is reduced and the armature can be operated at the desired high rate of speed without producing objectionable vibration of the entire apparatus.

Another feature of the invention which not only is adapted to reduce vibration of the apparatus but which is particularly designed

to secure a wide amplitude of movement of the movable cutter blade, consists in the use of a spring or springs acting directly on the cutter blade so as to tend to hold it in rest position yieldingly against movement in either direction. With this construction the springs can be designed so that the blade together with its spring or springs will have a natural period of vibration substantially equal to the frequency with which the blade is reciprocated or vibrated by the electro-magnet and armature. This feature of the invention is preferably used in connection with means acting on the armature tending to hold the armature away from the magnet poles in rest position yieldingly against movement in either direction. Accordingly another feature of the invention consists in the use of what may be termed a balanced spring system for returning the armature and the movable cutter blade to their rest positions and for yieldingly holding them against movement in these positions. In the construction hereinafter illustrated and described, this balanced spring system consists of two springs or sets of springs arranged to act respectively on the armature and on the movable cutter blade.

A further feature of the invention consists in arranging the spring or springs which act upon the movable cutter so that the cutter is not only held yieldingly in rest position but is also pressed yieldingly into engagement with the fixed cutter blade so that the armature or other driving part is relieved of this function and consequently the wear on the connection between the armature or other driving part and the movable cutter blade is reduced to a minimum.

The several features of the invention consists also in the devices, combinations, and arrangement of parts hereinafter described and claimed which, together with the advantages to be obtained thereby, will be readily understood by one skilled in the art from the following description taken in connection with the accompanying drawing.

Fig. 1 is a plan view of an electrically driven hair clipper embodying the several features of the invention with a portion of

the casing broken away to show parts beneath; Fig. 2 is a view in side elevation corresponding to Fig. 1; Fig. 3 is a detail plan view illustrating particularly the position of the armature and the springs when the armature is drawn toward the poles of the electro-magnet; and Fig. 4 is a detail view in side elevation of the armature.

The preferred embodiment of the present invention herein disclosed comprises a casing or support which also serves as a handle to be grasped by the operator, and carries at one end the customary fixed and movable cutters. The motive power for the clipper is to be supplied by an alternating current which acts through an electro-magnet to vibrate an armature cooperating therewith in synchronism with the alternations of the current. For the reasons hereinbefore stated, the armature is pivoted intermediate its ends, and the poles of the magnet are offset so as to act on opposite sides of the armature at opposite sides of the pivot. Coiled springs are provided which engage the rear end of the armature and tend to hold it yieldingly in rest position away from the poles of the electro-magnet. Two spring fingers or bars are also provided which engage slots in the movable cutter and tend to hold the cutter in rest position yieldingly against movement in either direction. These springs cooperate with the coil springs which engage the rear end of the armature and with them constitute a balanced spring system tending yieldingly to hold the armature and the movable cutter in their rest positions and enabling the armature and the cutter blade driven thereby to vibrate freely in synchronism with the alternating current.

Referring more specifically to the drawing, the casing or handle of the clipper is indicated at 6, and the stationary cutter at 8 rigidly secured to one end of the casing 6 by means of screws 10. A movable cutter blade 12 is mounted to reciprocate in ways 14 formed on the upper face of the fixed cutter.

The mechanism for actuating the movable cutter comprises an armature 16 which is mounted to move freely about a pivot 18 placed at a point intermediate the ends of the armature and is adapted to turn in bearings 19 formed in a skeleton frame 20 mounted within the support. The armature is built up of a series of thin laminations and a thick 55 lamination 22 which is elongated into a forwardly extending arm 24 adapted to engage a corresponding slot 26 formed in a block 28 on the movable cutter 12. At its rear end, the lamination or bar 22 extends upwardly 60 to form a seat for the springs controlling the movement of the armature.

The electro-magnet which cooperates with the armature comprises a field built up of thin laminations indicated at 30 and a coil 65 32 which is connected through a switch 34

and lead-in wires 36 to an outside source of alternating current.

In designing a clipper of the type herein disclosed which is adapted for use in a barber shop, it is desirable to arrange the operating elements to fit within a comparatively long, thin casing for convenience and ease in handling on the part of the operator. With the present construction, the armature is arranged to extend lengthwise of the casing 75 being connected at one end directly to the movable cutter. The coil 32 of the electro-magnet is placed beyond the free end of the armature and the ends of the laminations 30 comprising the field are carried forwardly 80 to form poles indicated respectively at 35 and 37. In order to secure the most efficient operation of the parts at high speeds and also to reduce vibration, the poles of the magnet are offset so that they act upon portions of the 85 armature on opposite sides of the pivot 18 to produce a balanced pull on the armature.

The armature is held yieldingly in rest position away from the poles 35 and 37 of the magnet by means of two coiled springs 40 and 42 which are interposed between two arms of the skeleton frame 20 and the rear end of the armature 16. An adjustment of the compression spring 40 may be effected to tune it as may be necessary or desirable by means 95 of a set screw 43 which is mounted in one arm of the skeleton frame 20 and forms a seat for one end of the spring. Preferably the spring 40 is so designed and arranged that the coils close up or seat before the armature comes 100 in contact with the poles, as indicated in Fig. 3. The spring thus forms a stop for the armature, and the noise and vibration which would result if the armature were allowed to come in contact with the poles is avoided.

In the present construction the action of the coiled springs 40 and 42 on the rear end of the armature is supplemented and balanced by the action of two spring fingers or bars 44 rigidly secured at their rear ends in a block 110 46 and at their forward ends engaging slots 48 extending transversely across the movable cutter 12. These spring fingers tend to hold the movable cutter in rest position yieldingly against movement in either direction, and in addition to cooperating with the springs 40 and 42 to tune the moving parts of the entire apparatus substantially to the frequency 115 of the alternating current, may be utilized, by designing them of the proper strength, to tune the natural period of vibration of the blade and springs to the frequency of the alternating current or to the rate of the movements imparted to the armature. A uniform and wide amplitude of movement is thus readily imparted to the movable blade, and wear and objectionable noise at the connecting points between the armature arm 24 and the block 28 is eliminated. With this construction 120 and arrangement of the springs for returning 125 130

the movable blade to its rest position, it will be seen that as the armature nears the limit of its movement in each direction, an increased resistance is built up in the springs 44 to arrest the further movement of the movable blade 12 and to provide a driving impulse for the blade in the opposite direction, so that the strain which would otherwise be thrown upon the pivotal connection between the armature and the blade 12 is reduced to a very small amount. Also, it is to be noted that the blade tuning springs 44 act in a direction opposite to that in which the armature tuning springs 40 and 42 act, whereby their reaction, tending to produce vibration of the entire apparatus, is partly neutralized.

In the present construction also, the requisite tension between the blades or, in other words, the pressure of the movable cutter against the fixed cutter, is secured through the spring fingers 44, and to this end the block 46 to which the fingers 44 are secured is mounted to rotate about an axis determined by two pivot pins 50 on corresponding arms 52 of the skeleton frame 20. The block 46 is acted upon by means of a coiled tension spring 54 secured at one end to the casing 6 of the clipper and at the other end to a hook-shaped member 56 projecting from the block 46, the arrangement being such that by the action of the spring 54 the fingers 44 are pressed yieldingly against the movable cutter. The movable cutter is thus held at all times in close contact with the fixed cutter by means acting independently of the driving connections, consisting of the arm 24 and the slotted block 28, between the armature and the movable cutter.

The nature and scope of the present invention having been indicated and an apparatus embodying the several features of the invention in their preferred form having been specifically described, what is claimed is:

1. A hair clipper having, in combination, a movable cutter blade, a cutter blade cooperating therewith, an electro-magnet, an armature movable towards and from the poles of the magnet and connected to the movable blade, and unitary spring tensioning means engaging the movable blade to press it against the cooperating blade and tending to hold the movable blade in rest position yieldingly against movement by the armature in either direction.

2. A hair clipper having, in combination, a movable blade, a blade cooperating therewith, an electro-magnet, a pivotally mounted armature pivotally connected to the movable blade and having a movement towards and from the poles of the magnet, spring means engaging the armature and tending to hold the armature in rest position away from the magnet poles yieldingly against movement in either direction, and additional spring means engaging the movable blade to press

it against the cutter blade and tending to hold the movable blade in rest position yieldingly against movement by the armature in either direction.

3. A hair clipper having, in combination, a casing, a movable blade mounted in the casing, a blade cooperating therewith, an electro-magnet, an armature for the electro-magnet mounted for movement toward and away from the poles of the magnet and connected to oscillate the movable blade, a spring member pivotally secured to the casing and tensioned to resist the pull of the electro-magnet on the armature and the blade, and additional spring means for moving the spring member about its pivotal connection with the casing to hold the movable blade yieldingly in contact with the cooperating blade.

4. A hair clipper having, in combination, a casing, a movable blade mounted in the casing, a blade cooperating therewith, an electro-magnet, an armature for the electro-magnet mounted for movement toward and away from the poles of the magnet and connected to oscillate the movable blade, a spring member pivotally mounted in the casing for movement towards and away from the movable blade and connected thereto to resist the pull of the electro-magnet on the armature and movable blade, and spring means tending to rotate the spring member about its pivot to hold the movable blade yieldingly in engagement with the cooperating blade.

5. A hair clipper having, in combination, a casing, a movable blade mounted in the casing, a blade cooperating therewith, an electro-magnet, an armature for the electro-magnet mounted for movement toward and away from the poles of the magnet, and connected to oscillate the movable blade, spring mechanism for moving the movable blade and armature in a direction contrary to the pull of the electro-magnet comprising parallel spring members engaging with the movable blade, a supporting bracket in which the spring members are carried pivotally mounted in the casing to move the spring members towards and away from the blades, and spring means tending to rotate the said bracket about its pivot in a direction to hold the movable blade yieldingly in engagement with the cooperating blade.

6. In a clipper, the combination with a casing, of a stationary clipper blade carried by the casing, a movable clipper blade cooperating therewith, guiding means for imparting to the movable blade a straight line movement parallel to the cutting face of the fixed blade, an electro-magnet, an armature mounted to swing about a pivot on the casing toward and away from the poles of the magnet and having a pivotal connection with the movable blade, spring means engaging the armature tending to hold the armature in an intermediate rest position away from the

magnet poles yieldingly against movement in either direction, and additional spring means engaging the movable blade and tending to hold the blade in an intermediate rest position yieldingly against movement by the armature in either direction, the said movable blade and additional spring means being arranged to comprise a separate unit having a natural period of vibration substantially equal to the impressed frequency of the armature.

7. In a clipper of the class described, the combination of a stationary blade, a movable blade arranged to move relatively to said stationary blade, mechanism engaging with the movable blade for imparting vibratory movements thereto, and a separate unitary, oscillating and tensioning means for said movable blade, said means comprising a spring member engaging with the movable blade arranged to cooperate with said vibratory mechanism to oscillate the movable blade, and to yieldingly engage the cooperating blades with each other.

8. In a clipper of the class described, the combination of a stationary blade, a movable cutter blade arranged to move relatively to said stationary blade, mechanism engaging with the movable blade for imparting vibratory movements thereto, and a separate unitary, oscillating and tension means for said movable cutter blade, said means comprising a pair of spring members engaging with the movable blade arranged to cooperate with said vibratory mechanism to oscillate the movable cutter blade, and to yieldingly engage the cooperating blades with each other.

9. In a clipper of the class described, the combination of a casing, a stationary blade secured to the casing, a movable cutter blade slidably mounted upon said stationary blade, and unitary, oscillating and tension means for said movable cutter blade, said means comprising parallel spring members engaging with the movable blade for controlling the oscillatory movements of the blade, a supporting bracket in which the spring members are carried pivotally mounted in the casing to move the spring member toward and away from the blades, and spring means tending to rotate said bracket about its pivot in a direction to hold the movable blade yieldingly in engagement with the cooperating blade.

In testimony whereof we have signed our names to this specification.

FREDERICK N. TOMPKINS.
IRVING O. MINER.
